UNITED STATES PATENT OFFICE.

FREDERICK J. LEDERER, OF BUFFALO, NEW YORK.

SPOOL HOLDER.

Application filed March 21, 1927. Serial No. 176,995.

This invention relates to a spool holder for holding spools of thread, wire or other strands and is especially designed for sewing-machines of the type used by manufacturers of garments wherein a plurality of spools are supported so that each spool may be brought to a feeding position when desired.

In the large tailoring establishments where garments of different and various styles are manufactured it is customary to support a series of spools of silk thread so that the operator can have the different colors readily accessible for carrying out his various sewing operations. While the spool holder is equally adaptable for other threads or yarns it is especially designed for the holding of spools of silk, since in these establishments a considerable loss is experienced by reason of the misplacement of the spools of silk or by the surreptitious removal of the spools from their unprotected holders.

The present invention has for its primary object to provide a spool holder in which the spools may be securely located or retained against accidental or unauthorized displacement. The invention also has for an object to provide a spool holder wherein the thread will be prevented from winding or tangling about the spindle as in the case where the thread rides off the lower end of the spool. The invention also resides in the novel form of spindle and spindle support or carrier whereby the spindle may be readily removed or lifted from its carrier and when in its operative position thereon will be securely held against wobbly or loose movement.

In the drawings:

Fig. 1 is a side elevation of the improved spool holder showing the locking plate inoperative and portions broken away for a clearer disclosure.

Fig. 2 is a similar view, in fragment, depicting the locking plate in its operative position.

Fig. 3 is a top plan view of the spool holder.

Fig. 4 is a similar view, partly broken away, of the spindle carrier.

Fig. 5 is a detailed cross sectional view about on line 5—5 of Fig. 4.

Fig. 6 is a plan view of a fragment of a slightly modified form of spindle carrier.

Fig. 7 is a detailed sectional view on line 55 7—7 of Fig. 6.

Proceeding in accordance with the present invention, there is provided a standard on which are relatively superposed a spool rest and a spindle carrier, the latter having a 60 series of seats for the reception of a like number of spindle elements which extend toward the spool rest for cooperatively supporting and holding a series of spools of 65 thread, the spools being normally held against displacement by the spool rest, and the spindles being movable to a position away from the spool rest to permit of the axial displacement of the individual spools 70 from their respective spindles. Means are provided for preventing the movement of the spindles from their normally operative 75 position and thereby securing the spools against unauthorized or accidental displacement, the spindle locking means preferably embodying a key-operated, or permutation, lock which will be accessible only to the person in possession of the key, or in possession of the combination when the permutation type of lock is used.

Referring more in detail to the accompanying drawings, the numeral 1 designates a supporting base from which rises a standard 2. A spool rest 3, in the form of a table or shelf, is preferably rotatably mounted on the standard 2 and is held against movement lengthwise thereof by a pair of pins or stops 4 on the standard. Superposed above the spool rest is a spindle carrier 5 consisting of a circular plate having a plurality 90 of seats defined, as by a stamping operation. The hub 6 of the spindle carrier is provided with an annular or peripheral keeper bead or shoulder 7 and is preferably removably secured to the carrier body by a clamping 95 nut 8. The spindle carrier is supported on the standard 2 against movement lengthwise thereof by a pair of pins or stops 9. The spindle carrier has its spindle seats radially arranged and each seat is defined by a pair of guide lugs or shoulders 10 struck up from the body of the plate and inwardly from the periphery thereof, a peripheral pocket 11 which is formed by striking down the material of the plate to form radial, depending flanges 12 substantially in alinement with the lugs 10, and a toe or anchor opening 13 arranged inwardly relative to said

lugs 10. The anchor or toe opening 13 is preferably formed by striking down the plate so as to form at the inner side thereof an abutment or rest 14.

Each spindle is preferably formed of a stiff wire which is bent into a substantially L-shape so as to form a spool engaging shaft 15, a supporting or suspending base 16, and an angular toe 17. In mounting or assembling each spindle, the toe 17 is inserted downwardly through the opening 13 and engaged in a notch or recess 18 formed in the abutment 14. The shaft 15 is then swung downwardly into the peripheral pocket 11 so as to engage between the lateral flanges 12 which tend to steady and hold the shaft against play, said flanges preferably resiliently clasping the shaft. This manipulation brings the base 16 down into flat seating engagement with the upper surface of the spindle carrier and between the spaced lugs or shoulders 10. By reason of the toe 17 engaging in the recess 18 of the abutment 14, the adjacent or inner end portion of the spindle is held against lifting or raising off the spindle carrier and the shaft 15 is further secured against lateral oscillatory or loose movement which might permit the spool to cant or tilt on the spool rest.

A locking cover or plate 19 is slidably mounted on the standard 2 above the spindle carrier, said locking plate having a hollow hub 20 in which is housed a coil spring 21 which is compressed between the inner end of the hollow hub and the hub 6 to normally exert a lifting force on the locking plate and thereby hold the same a spaced distance above the spindle carrier. A lock 22, which is preferably a key-operated spring lock, is carried by the locking plate so as to engage beneath the keeper shoulder 7 when the locking plate is depressed against the tension of the spring 21.

In operation, to mount a spool on a spindle it is necessary to first tilt or swing the spindle outwardly, such as is indicated by the dotted showing 23 in Figure 1. This removes the lower or free end of the shaft 15 outwardly beyond the spool rest a sufficient distance to permit of the ready application or threading of a spool over the lower end of said shaft. The spool and shaft are then swung backwardly to engage the shaft in the pocket 11, in which position the spool will rest upon said spool rest 3. After the several spools have been mounted on their respective spindles the locking plate 19 is depressed to a position wherein the lock 22 engages between the keeper shoulder 7, in which position the locking plate is held depressed by said lock. As will be observed from Figure 2 it will be noted that the locking plate substantially rests or seats upon the bases 16 of the several spindles and holds them against any upward tilting as well as

assists in securing them against loose or wobbly movement which would tend to tilt the spools on the spool rest. When in its inoperative position the locking plate will permit the ready removal of the spools and preferably will not permit a total displacement of the spindles. The upward movement of the locking plate is defined by a pin 24 which may be removed should it become necessary to raise the locking plate a sufficient distance to permit the entire removal or displacement of any or all of the spindles.

A set screw 25 is preferably provided in the hub 20 for being impinged against the standard 2 and thereby hold the locking plate against rotation about the standard. Cooperating with the carrier to hold it against turning relative to said locking plate, the latter is equipped with a depending pin 19' for normal engagement in a hole 5' provided for such purpose in the carrier 5. This interlock secures the carrier against turning at any time the screw 25 is set. Obviously the pin 19' could selectively engage in any of the holes 13 to one side of the toe 17.

In Figures 6 and 7 I have illustrated a slightly modified form of spindle carrier, the toe or anchor hole 26 comprising preferably a round aperture of sufficient size to receive the toe 17, and in place of the lugs 10 being struck up in a direction parallel to the base 16 I have struck them up in a transverse direction, as at 27, so that the inherent resiliency of the metal plate 5 will give to said lugs the desired springiness for resiliently grasping or gripping the base 16 and thereby secure the base to its seat even with the locking plate lifted.

By the use of a spool holder constructed in accordance with the present invention it will be impossible for anyone to unauthorizedly remove any spool from its spindle, and in order to effect any removal of a spool it is first necessary for the locking plate to be lifted, which can only be effected after the lock 22 is retracted from engagement with the keeper shoulder 7. Furthermore should the thread ride off the bottom of the spool, as when an excess of slack in the thread occurs, it will merely pass beneath the spool without engaging or twisting about any exposed spindle. Obviously, the holder is readily and equally adaptable for the securing of spools of wire or other strands without departing from the spirit of my invention.

I claim:

1. A spool holder comprising a standard, a spool-supporting table rotatable thereon, a spindle carrier also rotatable on the standard above the table, spindles carried by the carrier in depending relation thereto for holding spools on the table against displacement,

said spindles being upwardly displaceable to release the spools, and a locking cover plate for the carrier axially movable along the standard above the carrier for being moved 5 to a position in proximity to the spindles for preventing upward displacement of the latter.

2. A spool holder comprising a supporting base having a standard rising therefrom, 10 a spool table on the standard, a spindle carrier supported above the table by the standard, said carrier having a spindle seat, a spindle hung in said seat and extending downwardly toward the table for entering 15 the bore of a spool, said spindle being outwardly swingable away from the table to permit removal of the spool, and a locking member designed to arrest the outward swinging of the spindle.

20 3. A spool holder comprising a standard, a spool rest, a spindle carrier, said rest and carrier being arranged on the standard in relatively superposed and spaced positions, said carrier having a spindle seat, a spindle en- 25 gaged in the seat and operatively extending toward the rest to cooperatively hold a spool against displacement, said spindle being movable to a position away from the rest to permit the application and removal of a 30 spool, and means movable on the standard for locking the spindle in its seat.

4. A spool holder comprising a standard, a spool rest, a spindle carrier, said rest and carrier being relatively superposed on said 35 standard and said carrier having a plurality of spindle seats defined by a plurality of peripheral pockets formed in the carrier together with an anchor opening arranged inwardly from each pocket and spaced lugs 40 arranged between each pocket and its related anchor opening, a plurality of substantially L-shaped spindles having their base portions engaged on said seats and their shaft portions engaging in said pockets, each base 45 portion having on its free inner end an angular toe for engaging in the respective anchor opening in interlocking relation therewith, and means for securing said spindles on their seats, the shaft portions of said 50 spindles extending toward the spool rest.

5. A spool holder comprising a standard, a spool rest, a spindle carrier, said rest and carrier being relatively superposed on said standard and said carrier having a plurality 55 of spindle seats defined by a plurality of peripheral pockets formed in the carrier together with inwardly arranged anchor openings, a plurality of spindles having base portions lying radially of the carrier and en- 60 gaged on said seats, a shaft portion depending from the outer end of each base and engaging in said pockets, each base portion having on its free inner end an angular toe for engaging in the respective anchor open-

ing in interlocking relation therewith, said 65 spindle shafts extending toward the spool rest and adapted to be tilted outwardly for applying or removing a spool, said base portions during such tilting operation raising off their seats, and means for locking the 70 base portions to their seats.

6. A spool holder comprising a standard, a spool rest, a spindle carrier, said rest and carrier being relatively superposed on said standard and said carrier having a plurality 75 of spindle seats each having an inwardly arranged anchor opening, a plurality of substantially L-shaped spindles having their base portions engaged on said seats and their shaft portions extending over the peripheral 80 portion of the carrier toward said spool rest, each base portion having on its free inner end an angular toe for engaging in the respective anchor opening in interlocking relation therewith, and a locking plate slidable 85 on the standard toward the bases for securing them on their seats.

7. A spool holder comprising a standard, a spool rest, a spindle carrier, said rest and carrier being relatively superposed on said 90 standard and said carrier having a plurality of spindle seats, a plurality of spindles displaceably engaged on said seats and extending toward said spool rest, a locking plate 95 slidable on the standard toward and from the spindle carrier for securing the bases to their seats, and means for operatively connecting the locking plate to said spindle carrier.

8. A spool holder comprising a standard, a spool rest, a spindle carrier, said rest and carrier being arranged on the standard in relatively superposed and spaced positions, said carrier having a spindle seat, a spindle engaged on the seat and operatively extending toward the rest to hold a spool thereon, said spindle being movable to a position away from the rest to permit the application and removal of a spool, a keeper carried by said spindle carrier, and a locking plate slid- 100 able on the standard and movable to a position for interlockingly engaging said keeper 105 for securing the spindle in its operative position.

9. A spool holder comprising a standard, a spool rest thereon, a spindle carrier arranged on the standard above the rest and having an opening arranged inwardly from the marginal portion of said carrier, a spindle hung on the carrier and having a depending spool-supporting shaft extending toward the spool rest, said spindle having an inwardly extended toe for anchoring engagement in the opening of said carrier, and means for locking the spindle down onto the 115 carrier.
